(57) **CLAIM**

The ornamental design for the quilt clip, as shown and described.

DESCRIPTION

FIG. 1 is a top view of the clip of the invention.

FIG. 2 is a bottom view of the clip of FIG. 1.

FIG. 3 is a side view of the clip of FIG. 1.

FIG. 4 is the opposing side view of the clip of FIG. 1.

FIG. 5 is a front end view of the clip of FIG. 1.

FIG. 6 is a back end view of the clip of FIG. 1

FIG. 7 is a schematic of a top view of the clip shown in FIG. 1 without the bottom of the clip.

FIG. 8 is a schematic perspective view of the top of the clip of FIG. 7.

FIG. 9 is a schematic of the opposing side view of the clip shown in FIG. 4 without the bottom of the clip; and,

FIG. 10 is a schematic of a bottom view of the clip shown in FIG. 2 without the top of the clip.
